UNITED STATES PATENT OFFICE.

ROBERT BROWN, OF TOLEDO, OHIO.

ENGINE-MUFFLER.

1,290,065.

Specification of Letters Patent.

Patented Jan. 7, 1919.

Application filed May 15, 1918. Serial No. 234,585.

To all whom it may concern:

Be it known that I, ROBERT BROWN, a citizen of the United States, residing at Toledo, in the county of Lucas, State of Ohio, have 5 invented a new and useful Engine-Muffler; and I do hereby declare the following to be a full, clear, and exact description of the invention, such as will enable others skilled in the art to which it appertains to make and

10 use the same.

The present invention relates to a muffler for silencing the exhaust from internal combustion engines, and has for its object to provide a device of this character which is inexpensive in its construction and embodies 15 novel features of design whereby it will act in a most effective manner to silence the exhaust without producing any undue back pressure upon the engine.

20 Further objects of the invention are to provide an engine muffler which can be inexpensively constructed from sheet material, which has a compact formation and can be mounted without difficulty in the space provided under the body of a motor vehicle, which will not burst or get out of repair, and which can be easily assembled or taken apart.

25 With these and other objects in view, the invention consists in certain novel combinations and arrangements of the parts as will more fully appear as the description proceeds, the novel features thereof being pointed out in the appended claims.

30 For a full understanding of the invention, reference is to be had to the following description and accompanying drawings, in which:—

35 Figure 1 is a horizontal sectional view through a muffler constructed in accordance 40 with the invention.

Fig. 2 is a transverse sectional view on the line 2—2 of Fig. 1, looking in the direction of the arrow.

Fig. 3 is a side elevation of the complete 45 muffler.

Corresponding and like parts are referred to in the following description and indicated in all the views of the drawings by the same reference characters.

50 Referring to the drawings, which illustrate one possible embodiment of the invention, the numerals 1 designate flanged top and bottom plates which are clamped against the upper and lower edges of the side walls 55 2 and coöperate therewith to form the body

of the muffler. The muffler body has an elongated formation, one end A thereof being square, while the other end B thereof is round. The side walls 2 are formed from a continuous strip of sheet material which has a width corresponding to the thickness of the muffler body, the said sheet material being bent into a shape corresponding to that of the body, and having the ends thereof overlapped and riveted at one of the corners of the body, as indicated at 3. The peripheral flanges 1^a of the plates 1 fit around and embrace the upper and lower edges of the side walls 2 and are clamped tightly in position by means of the bolts 4.

The inlet pipe 5 which conveys the exhaust gases directly from the engine to the muffler communicates with the interior of the body through the square end A thereof, the extremity of the inlet pipe being preferably flanged at 5^a so that it can be secured without difficulty to the side walls 2. The outlet opening 6 through which the exhaust gases leave the muffler body is arranged at one side of the muffler and at an intermediate point in the length thereof. A downwardly curved outlet pipe 7 is shown as applied to the exterior of the muffler casing and arranged to receive the gases as they merge through the outlet opening 6. This curved outlet pipe 7 is illustrated as being flanged at 7^a so that it can be readily riveted or otherwise attached to the muffler body, and it will be obvious that this curved pipe serves to direct the hot exhaust gases downwardly away from the body of the motor vehicle to which the muffler is applied.

A pair of spiral strips 8 and 9 extend inwardly from one side of the muffler casing, being riveted or otherwise secured to the side walls 2 on opposite sides of the outlet opening 6, as indicated at 10, and coöperating with each other and with the curved end B of the muffler body to provide a tortuous path through which the exhaust gases are caused to travel before they are finally discharged into the atmosphere. These spiral strips 8 and 9 have a width corresponding to that of the side walls 2 so that the upper and lower edges thereof are engaged by the flanged top and bottom plates 1, and the free ends of the spiral strips terminate in sleeves 11 which receive a pair of the bolts 4. Those bolts passing through the sleeves 11 thus serve both to hold the inner ends of the

spiral strips 8 and 9 rigidly in proper relation to each other, and also to connect the top and bottom plates 1 and retain the parts of the muffler tightly together. The spiral strip 8 is longer than the strip 9 and the inner end portion thereof coöperates with the curved end B of the muffler body to provide a curved passage D which receives the exhaust gases after they have initially been 5 permitted to expand in the large chamber A at the square end of the muffler body. From the passage D the exhaust gases enter the narrow passage E provided between the two spiral strips 8 and 9, said passage E serving 10 to conduct the exhaust gases to the outlet pipe 7. After the exhaust gases have passed through the muffler they are finally discharged downwardly through the outlet pipe 7, and the exhaust from the engine is thus 15 silenced without producing any undue back pressure thereon.

Having thus described the invention, what I claim as new and desire to secure by Letters Patent, is:—

25 1. An engine muffler including an elongated flat casing having one end thereof curved and provided at its opposite end with an inlet opening, an outlet opening being provided at one side of the casing, and spiral 30 strips extending into the casing from opposite sides of the outlet opening and coöperating with the curved end of the casing and with each other to provide a tortuous path for conducting the products of combustion to the outlet opening.

2. An engine muffler including an elongated flat casing having one end thereof curved and the other end thereof provided with an inlet opening, an outlet opening being 40 provided in one side of the casing, spiral strips extending into the casing from opposite sides of the outlet opening and coöperating with the curved end of the casing and with each other to provide a tortuous path 45 for the products of combustion, the inner ends of the spiral strips terminating in sleeves, and fastening members extending

through the casing and engaging the sleeves to hold the spiral strips in proper position.

3. An engine muffler including an elongated flat casing having removable top and bottom plates and having an inlet opening in one end thereof, the opposite end of the casing being rounded and an outlet opening being provided at an intermediate point in 55 one side of the casing, a pair of spiral strips extending into the casing from opposite sides of the outlet opening and coöperating with each other and with the rounded end of the casing to provide a tortuous path for 60 the products of combustion, and clamping bolts connecting the top and bottom plates and engaging the inner ends of the spiral strips to hold the same in proper position.

4. An engine muffler including an elongated flat casing formed with annular side walls and removable top and bottom plates fitting against the upper and lower edges of the side walls, the side walls being provided at one end of the casing with an inlet opening and being curved at the opposite end of the casing, an outlet opening being provided at one side of the casing, spiral strips extending into the casing and having the outer ends thereof secured to the side walls on opposite sides of the outlet opening, the strips having a width corresponding to the width of the side walls and coöperating with each other and the curved ends of the casing to provide a tortuous path for the products of combustion, clamping bolts connecting the removable top and bottom plates and engaging the inner ends of the spiral strips to hold them in proper relation, and a curved outlet pipe applied to the casing and communicating with the outlet opening.

In testimony whereof I have signed my name to this specification in the presence of two subscribing witnesses.

ROBERT BROWN.
